CHAIR TRAY

Albin K. Peterson and Hampden Wentworth, Redondo Beach, Calif., assignors to Longren Aircraft Company, Torrance, Calif., a corporation of California

Application May 22, 1948, Serial No. 28,626

4 Claims. (Cl. 155—127)

1

This invention relates to a simple and effective tray arranged to be removably attached to chairs and, more particularly, to baby chairs.

Baby chairs having pivotally connected trays have heretofore been provided; however, such chairs known to us are impractical due to their construction and weight for use in automobiles, transporting to and from restaurants, and for general utility during vacationing, visiting and the like. Prior, pivotally connected trays did not impart added strength or rigidity to the entire chair, permitted the child to readily lift and spill the contents of the tray, and interfered with the placement or removal of a child in a chair. Various types of baby chairs have been provided for carrying along wherever their use may be desired. Such chairs are light in weight, particularly those constructed from aluminum tubing or other light-weight material.

The present invention is particularly directed to a simple and efficient tray construction, the tray being arranged for use with a chair having a pair of forwardly and downwardly curving arms connected by a cross member above the level of the seat of such chair. We have discovered that by providing a light-weight tray, which may be stamped from light-weight material, such as aluminum, and provided with a groove along its inner side for engaging and receiving the transverse cross piece connecting the chair arms, the tray may be supported in a cantilever manner by providing downwardly extending brackets on each end side thereof, the brackets being provided with a spring snap-on connection for engaging the upper ends of the front legs of the chair.

This particular manner of attaching the tray to the chair does not only render the tray easily and quickly attached or detached from the chair but provides a rigid cantilever support which will positively prevent the tray from being unintentionally detached from the chair.

It is a primary object of this invention to provide a cantilever support for detachably mounting a tray onto a chair.

Another object is to provide a light-weight chair attachment that may be stamped from a single piece of material and provided with snap-on connections for rigidly maintaining the tray in assembled relation on a chair.

A further object is to provide a chair attachment so constructed as to utilize the transverse member connecting the arms of a baby chair for supporting the tray.

A still further object is to provide a chair attachment that may be readily and easily attached

2

or detached from a chair which will be durable, efficient in operation, and which may be provided at a very small cost.

The above and other objects will be made apparent throughout the further description of the invention when taken in connection with the accompanying drawings, wherein like reference characters refer to like parts. It is to be specifically understood that the drawings are not a definition of the invention but merely illustrate an exemplary form by means of which the invention may be effectuated.

In the drawings:

Fig. 1 is a perspective view of a chair having a tray mounted thereon embodying the invention.

Fig. 2 is a sectional view taken along the line II—II of Fig. 1.

Fig. 3 is a sectional view taken along the line III—III of Fig. 2.

Fig. 4 is a sectional view taken along the line IV—IV of Fig. 2.

Referring to the drawings, the invention is illustrated in connection with one type of a chair for which the present tray is specifically designed. This type of a chair consists of a tubular framework of a light-weight material, such as aluminum tubing or the like. The supporting structure of the chair may be of a single piece of tubing bent in the form of a U, the legs of the U forming the front legs 11 and 12, the arms 13 and 14, and upstanding back supports 15 and 16. The arms 13 and 14 are forwardly and downwardly curved into the front legs 11 and 12 which are connected by the cross piece 17. The arms 13 themselves are also connected by means of a horizontally extending cross member 18. The seat itself may be made of canvas and include a front tongue removably connectable with the cross member 18, the entire seat being removable by a sliding motion along the arms and vertical back portions of the supporting frame. It will be noted that the level of the seat is below the level of the cross member 18.

The present tray may be made from a single piece of sheet material, such as aluminum or steel, represented in its entirety by 19, having depending from the sides thereof brackets 21 and 22. The tray 19 is stamped to provide a central depression having a bottom 23 having substantially vertical front and rear side walls 24 and 25, respectively, and substantially vertical end walls 26 and 27. The front wall 24 and end walls 26 and 27 terminate in outwardly extending, substantially horizontal flanges 28, 29, and 31, respectively. The flanges 28, 29, and 31 merge to

gether and are rounded to form a continuous flange about the front and sides of the tray. The upper end of the rear wall 25 terminates in a substantially flat, horizontal portion 32, the latter terminating in a downwardly extending lip or flange 33, forming a groove 34 in the lower surface of the tray, the groove being defined by the rear wall 25, horizontal portion 32 and the downwardly extending flange 33. The ends of the horizontal portion 32 merge into the inner ends of the flanges 29 and 31, completing a continuous, substantially horizontal flange surrounding the upper edges of the walls 24, 25, 26 and 27.

The downwardly extending flange 33 is recessed at each of its ends, as shown at 35, for accommodating and receiving the cooperating portions of the arms 13 and 14.

The brackets 21 and 22 depend from the outer edges of the flanges 29 and 31, respectively, and are arranged to cover the outer surfaces of curved portions of the arms. Each of the brackets may terminate at its upper edge with an inwardly turned flange 36, on which the opposing surfaces of the flanges 29 and 31 rest. The flanges 36 may be affixed to the flanges 29 and 31 by any suitable means, such as rivets 37, or by welding. Each of the brackets 21 and 22 extends from the rear end of the flanges 29 and 31 to a point rearwardly of the forward end of the flanges 29 and 31. The brackets are somewhat triangular in shape and provide a downwardly and inwardly curved forward end, the latter terminating in an inwardly extending flange 41. The flange 41 terminates short of the lower end of the bracket, as shown at 42. The lower ends of the flange 41 are positioned to engage the cooperating portion of the legs 11 and 12 and provide a support for the outer portion of the tray 19, the brackets terminating downwardly and inwardly from the lower ends of the flanges 41 and arranged to overlie the opposing sides of the legs 11 and 12, the bottoms of the brackets 21 and 22 extending upwardly and rearwardly from the lower front ends of the brackets to the rear ends of the brackets, as shown at 43.

Means is provided for releasably attaching each of the brackets 21 and 22 to the legs 11 and 12, respectively. In the form shown, the attaching means consists of a spring snap-on connection, represented in its entirety by 44 (see Fig. 4), positioned adjacent the lower end of each of the flanges 41 and fixed to the adjacent portions of the flanges 21 and 22. The connecting means 44 consists of a flat flange portion 45 adapted to lie flush against the opposing portion of its associated flange and fixed thereto by any suitable means, such as brads 46. The rearwardly extending portion of the means 44 consists of a curved spring portion 47 terminating in a backwardly turned, beaded, free end 48, spaced from the opposing portion of its associated bracket.

It now can be understood that the present tray may be attached to the chair by inserting the groove 34 provided at the rear side of the tray over the transverse cross piece 18 and the tray moved downwardly to cause the snap-on means 44 to engage the legs 11 and 12 and that the tray may be readily removed from the chair by lifting the outer end of the tray upwardly, disconnecting the means 44 from the legs 11 and 12.

It will be noted that the weight of the tray is carried by the contact of the cross member 18 with the inner side walls of the groove 34 and the lower end of the flange 41, as shown at 42, and that the portions of the flanges overlying the

curved intersection of the arms and legs will prevent any lateral movement of the tray. It is also to be noted that the shoulder 42 contacts the downwardly curving portions of the arms 11 and 12 at a point in front of and below the level of the cross member 18, thus imparting great stability to the tray when it is in position on a chair.

Accordingly, there is provided a detachable tray for baby chairs employing a cross piece connecting the arms of the chair adjacent the outer ends thereof. The present tray is simple in construction, durable, provided with cantilever means for rigidly supporting the tray, which means may be readily and easily attached or detached from the chair. The tray is light-weight, simple in construction and may be provided at a very small cost.

While I have illustrated and described one form of the present invention, it will now be apparent to those skilled in the art that certain changes, modifications, additions, and omissions may be made in the exemplary form illustrated and described without departing from the spirit and scope of the invention as defined by the appended claims.

We claim:

1. A removable tray arranged for use with a child's chair, having a pair of forwardly and downwardly curving arms connected by a cross member above the level of the seat of such chair, comprising: a body portion having a depressed central area; a downwardly extending lip along the rear margin of the body portion, said lip cooperating with a wall of the depressed central area to form a groove in the lower surface of the tray arranged to receive the cross member of the chair; a downwardly extending bracket at each side of the tray, each of said brackets being provided with an inwardly extending curved flange having a margin arranged to abut a downwardly curved portion of a chair arm at a point in front and below the level of the cross member; and resilient means at the extremity of the flange carried by each bracket and cooperating with the flange for grasping an arm.

2. A removable tray arranged for use with a child's chair, having a pair of forwardly and downwardly curving arms connected by a cross member above the level of the seat of such chair, comprising: a body portion having a depressed central area; a downwardly extending lip along the rear margin of the body portion, said lip being integral with the body portion and presenting a curved surface therebetween, said lip cooperating with a wall of the depressed central area to form a groove in the lower surface of the tray arranged to receive the cross member of the chair; a downwardly extending bracket at each side of the tray, each of said brackets being provided with an inwardly extending downwardly curved flange having a margin arranged to abut a downwardly curved portion of a chair arm at a point in front and below the level of the cross member; and resilient means including a spring clip carried by each bracket and cooperating with the flange for grasping an arm.

3. The combination with a chair having spaced supporting legs, spaced arms intersecting the upper ends of said legs and a cross member connecting said arms adjacent said intersection, of a tray having a bottom, upstanding side and end walls terminating in substantially horizontally disposed flanges, the adjacent ends of said flanges merging together to form a continuous flange surrounding the upper ends of said walls, one of

said flanges terminating in a downwardly extending flange forming an inverted, U-shaped groove along one side of said tray, said groove adapted to engage and receive said cross member, and means depending from the said end flanges for engaging the said legs adjacent said intersection, the said means including a bracket, the outer end of said bracket terminating in an inwardly extending curved flange extending from the top thereof to a point adjacent the inner surface thereof, the bottom of said flange being arranged to rest upon the opposing portion of its cooperating leg, and a spring clip carried adjacent the extremity of said bracket and cooperating with said flange for clamping said bracket in tight engagement with said leg.

4. A removable tray arranged for use with a child's chair, having a pair of forwardly and downwardly curving arms connected by a cross member above the level of the seat of such chair, comprising: a body portion having a depressed central area; a downwardly extending lip along the rear margin of the body portion, said lip cooperating with a wall of the depressed central area to form a groove in the lower surface of the

10

15

20

25

tray arranged to receive the cross member of the chair; a downwardly extending bracket at each side of the tray forwardly of the cross member, each of said brackets being provided with an inwardly extending, downwardly curved flange along one edge margin arranged to engage a downwardly curved portion of a chair arm at a point in front and below the level of the cross member; a spring clip carried adjacent the lower end of each bracket and cooperable with the point of engagement of the inwardly extending flange to tightly grasp a portion of an arm.
